UNITED STATES PATENT OFFICE.

BAZEL E. CARRM, OF NEW YORK, N. Y.

DESIGN FOR A DISPLAY STAND.

Application filed July 31, 1926. Serial No. 18,561. Term of patent 14 years.

To all whom it may concern:

Be it known that I, BAZEL E. CARRM, a citizen of the United States, residing at the city of New York, borough of Manhattan, in the county and State of New York, have invented or produced a new, original, and ornamental Design for Display Stand, of which the following is a specification, reference being had to the accompanying drawing, forming a part thereof.

In the drawing—

The figure is a perspective view showing a display stand embodying my said invention.

I claim:

The ornamental design for a display stand, as shown.

BAZEL E. CARRM.
